Primary Examiner — Jennifer Rivard*Assistant Examiner* — April Rivas(74) *Attorney, Agent, or Firm* — William W. Cochran; Cochran Freund & Young LLC(57) **CLAIM**

The ornamental design for a locking container, as shown and described.

DESCRIPTION

FIG. 1 is a top isometric view of a locking container showing my new design in an open and unlocked configuration.

FIG. 2 is a front view of the locking container in a closed configuration.

FIG. 3 is a back view thereof.

FIG. 4 is a bottom view thereof.

FIG. 5 is a top view thereof.

FIG. 6 is a left side view thereof; and,

FIG. 7 is a right side view thereof.

1 Claim, 5 Drawing Sheets
